UNITED STATES PATENT OFFICE.

LOUIS EUGÈNE CLEMENCET, OF PARIS, FRANCE.

WIRE-STRETCHING DEVICE.

Application filed November 6, 1925, Serial No. 67,301, and in France November 15, 1924.

The present invention relates to stretching devices; and its object, stated briefly, is to provide an improved device for readily and effectively stretching and tightening 5 threads, wires, ropes, cables and other flexible elements of like character, regardless of their material, which can be mounted instantly thereon without requiring any splicing or fastening.

10 In the accompanying drawings:

Figure 1 is a front view of a stretching device constructed according to the invention;

15 Figs. 2 and 3 are, respectively, a plan view and a side view thereof;

Fig. 4 is a view taken from the opposite side;

Fig. 5 is a cross-section on line 5—5, Fig. 1;

20 Fig. 6 is a view showing the stretcher previous to its hooks being engaged with the material to be stretched;

Fig. 7 is a view showing one hook being engaged, and Fig. 8 shows the engagement 25 of the other hook;

Fig. 9 is a view showing the stretching device with both hooks engaged;

Figs. 10 and 11 are cross-sections on lines 10—10 and 11—11, respectively, of Fig. 9.

30 The improved stretching device consists of a single metal strip or part A that is bent to form an open, rectangular or annular member or loop a, the two branches b and c of which are arranged in such a way that one of them (branch c, for example) passes in front of the other branch b and then curves away from it to form the branch proper; said branches leaving some clearance between them. As will be apparent 35 from Fig. 4, the branches are, in fact, wound one-quarter of a turn over each other, and are provided with terminal hooks d and d' for engagement with the wire B or other flexible element to be stretched.

40 To facilitate positioning, and to permit the stretching device to be rotated, the arms or portions of the branches b and c located above loop a are inclined upwardly away from the loop at an angle to the horizontal, and extend in such directions as virtually to 45 occupy a common vertical plane to which the plane of the loop is perpendicular; the terminal hooks d and d' on said arms or branches thus being so disposed as to normally clear the wire. Hence, the latter can 50 readily be passed between the arms or

branches and a stick C or the like then inserted through the loop a, whereafter the device can be turned in the direction of arrow f by means of such stick or lever, thereby winding the wire around it, as will be 60 understood from Fig. 6. This winding of the wire will, of course, have the effect of exerting tension upon the two portions thereof at opposite sides of the device in the direction of arrows m and m' and, in consequence, 65 of stretching the wire.

The device can then be locked to the wire to maintain the latter in taut condition, by connecting the hooks thereto; and to effect this, the stick or handle C is first raised or 70 moved upward in the direction of arrow V (Fig. 7), thereby tilting the device so as to engage the hook d' of arm c with the wire. Thereafter the stick is swung downward in the direction of arrow V' (Fig. 8), which 75 tilts the device clockwise and secures the hook d of arm b or, if preferred, this movement can be obtained by withdrawing the stick from loop a and re-inserting it from the opposite side, and then raising it, as indicated by arrow V² and the dot-and-dash lines in Fig. 8. Fig. 9 shows the device secured to the wire.

80 The engagement of the hooks with the wire is facilitated by positioning the loop a in a plane which is perpendicular to the vertical plane wherein both arms b and c virtually lie, as has already been stated, because the stick or other operating element C will likewise occupy such vertical plane, as 85 will be understood. Furthermore, the stick, instead of being engaged at its end only with the loop, may be inserted therethrough up to its central portion and then grasped and operated from either end or from both 90 ends; and if preferred, the loop may be manipulated by means of a wrench or other suitable gripping element which is directly engaged with it, in place of the stick or handle C. Also, while it is preferred to wind 95 the two arms over each other merely to the extent of a quarter-turn, they may be wound an amount which is a multiple of a quarter-turn provided, of course, that the plane of the loop maintains its perpendicular disposition with relation to the plane of said arms.

100 Due to the inclination of arms b and c, as above described, both hooks d and d' will be clear of the wire during the actual stretching operation; whereas, after one hook 110 (d', for instance) has been engaged with

the wire at the conclusion of said operation, there will be no danger of that hook becoming detached while the other hook is being engaged (Figs. 6, 7 and 8). It is also advisable to arrange both hooks (or either of them) at a slant to the axis of rotation of loop a ; but it will be sufficient if the free arms X and X' of the hooks slant, and in either case the amount or degree of slant 10 may vary, Fig. 5 showing in dotted lines a hook d^2 whose free arm X^2 is perpendicular to the plane of rotation of the loop. Finally, it is possible to further decrease the liability of one hook becoming disengaged during the attachment of the other hook to the wire—particularly if the hooks are straight and only their free arms slant—by making the free arm of one hook longer than that of the other hook, in which case 20 the hook with the longer arm will be engaged first. Figs. 10 and 11 illustrate this feature, the free arm X' of hook d' (Fig. 11) having a length greater by the amount y (Fig. 10) than the arm X of hook d .

25 Claims:

1. A stretching device for wires and the like, comprising a metal strip bent upon itself to form an open central loop whereby it may be rotated, and a pair of arms branching from such loop and wound over each other at their inner ends; said arms extending upwardly away from the loop at an angle to the horizontal and in such directions as virtually to occupy a common vertical plane to which the plane of the loop is perpendicular; both arms having hooks 30 at their free outer ends for engagement at the same time with the wire, such hooks being arranged at a slant to the axis of rotation of the loop and having arms of unequal lengths.

2. A stretching device for wires and the like, comprising a metal strip bent upon itself to form an open central loop whereby it may be rotated, and a pair of arms branching from such loop and wound over each other at their inner ends; said arms extending upwardly away from the loop at an angle to the horizontal and in such directions as virtually to occupy a common vertical plane to which the plane of the loop is perpendicular; both arms having hooks 40 at their free outer ends for engagement at the same time with the wire.

2. A stretching device for wires and the like, comprising a metal strip bent upon itself to form an open central loop whereby it may be rotated, and a pair of arms branching from such loop and wound over each other at their inner ends; said arms extending upwardly away from the loop at an angle to the horizontal and in such directions as virtually to occupy a common vertical plane to which the plane of the loop is perpendicular; both arms having hooks 45 at their free outer ends for engagement at the same time with the wire, such hooks being arranged at a slant to the axis of rotation of the loop.

3. A stretching device for wires and the like, comprising a metal strip bent upon itself to form an open central loop whereby it may be rotated, and a pair of arms branching from such loop and wound over each other at their inner ends; said arms extending upwardly away from the loop at an angle to the horizontal and in such directions as virtually to occupy a common vertical plane to which the plane of the loop is perpendicular; both arms having hooks 55 at their free outer ends for engagement at the same time with the wire, such hooks being arranged at a slant to the axis of rotation of the loop and having arms of unequal lengths.

In testimony whereof I affix my signature.

LOUIS EUGÈNE CLÉMENCET.
